UNITED STATES PATENT OFFICE

JOHN W. YOUNG, OF PITTSBURGH, PENNSYLVANIA

GAS PROTECTIVE APPARATUS

Application filed July 11, 1930. Serial No. 467,328.

This invention relates to protective apparatus for banks and similar institutions and more especially it is directed to a gas generating and dispersing devices adapted to be located at various points of advantage within the bank.

One object of this invention is to provide a remote controlled gas generator and dispersing means to be mounted preferably above the cashier or teller windows so that when in operation, a curtain of temporarily incapacitating gas will be erected in a vertical plane immediately in advance of the window.

Another object of this invention is to effect a gas generating and dispersing device which may be instantly set into operation by the cashier or teller when confronted by the command, "hands up", whereupon the bandit demanding the bank deposits will be immediately enveloped by the gas and easily captured.

Another object of this invention is to produce an apparatus of the character designated which may be easily placed in position, quickly and readily replenished, and so constructed as to be concealed from casual observation.

With these and other objects in view, which will become apparent as the description proceeds, the invention resides in the construction, combination and arrangement of parts, hereinafter more fully described and claimed, and illustrated in the accompanying drawings, in which like characters of reference indicate like parts throughout the several figures, of which:

Fig. 1 is a fragmentary elevation of a bank window illustrating the gas generator and dispersing means located thereabove.

Fig. 2 is a fragmentary vertical section taken on the line 2-2 of Fig. 1.

Fig. 3 is a horizontal section of the generator on the line 3-3 of Fig. 2.

Fig. 4 is a fragmentary vertical section illustrating a modified form of gas generator and dispersing means mounted on the upper service of the bank window.

Fig. 5 is a fragmentary front elevation with parts shown in dotted outline.

Fig. 6 is a front elevation of a bank window illustrating the apparatus shown in Figs. 4 and 5, invention operatively positioned above the bank window, and,

Fig. 7 is a fragmentary vertical section on the line 7-7 of Fig. 6.

Briefly stated, this invention consists of a generator including a body portion, a cartridge chamber, a plurality of outlets extending from the cartridge chamber to the exterior of the generator and an electrically controlled cartridge or similar gas generating means situated within the chamber whereupon when the cartridge is ignited, the chemical agent will be projected to form a curtain of gas immediately in advance of the window.

To adequately protect the deposits of their patrons, many commercial institutions have resorted to the use of a temporarily incapacitating agent and it is therefore the fundamental aim and purpose of this invention to provide a device which will augment the development of this field of property protection and enable the cashier or teller of a bank to instantly subject a bandit demanding the bank deposits to the full action of the gas without apparently moving from his position.

In Figs. 1, 2, 3, and 4 there is shown a gas generating and dispersing apparatus A adapted to be suitably mounted above the cashier's or teller's window B.

This device comprises a body portion (1) having therein a longitudinally extending opening (2) closed at one end and open at its other as at (3). A plurality of discharge passages (4) extend from the chamber (2) to the exterior of the generator, said passages opening through the bottom of the generator as at (5), said openings being normally closed by a plug of suitable material (6).

Within the chamber (2) is deposited a gas cartridge (7), the dimensions of which correspond substantially to those of said chamber. This cartridge (7) includes a temporarily incapacitating gas and a combustible mixture for projecting the gas under pressure through the various outlets.

The combustible mixture is ignited by a

resistance (8) connected to terminals (9) projecting from the ends of the cartridge and adapted to project in suitable recesses in plug (10), said recesses containing contacts included in a suitable electric circuit.

Within the electrical circuit are suitable switches, which latter are situated within ready access to the cashier or teller so that when said switch is closed, the resistance element being energized will ignite the combustible mixture and cause the temporary incapacitating agent to be projected under pressure in a plane immediately in advance of the window as will be readily understood from Fig. 2 of the drawings.

In the modifications shown in Figs. 4 to 7 of the drawings there is disclosed a gas generator and dispersing means wherein the outlet passages (4') extend radially from the cartridge chamber (2). This chamber is closed by a threaded plug (11) suitably threaded in the open end (12) of the generator as clearly shown in Fig. 4. Plug (11) is centrally bored for passage of the conductors (13) connected to resistance (14) located in the combustible mixture of the cartridge.

The preceding structure, while quite analogous to that originally described has been found to be more advantageous under certain circumstances in effecting dispersion of the gas.

In conclusion it is manifest this invention provides a simple, easily charged generator which may be mounted above the window so that when set into operation, the gas discharging through the outlets will completely envelope the bandit standing in front of the window to render him helpless and permit of his ready capture.

Having thus described my invention, what I desire protected by Letters Patent is as set forth in the following claims:

1. A gas protective apparatus comprising a gas generator and means in connection therewith for producing a vertical sheet of gas immediately beneath the generator said means including a body portion having a cartridge chamber, a gas producing cartridge disposed within the chamber, means for igniting the cartridge and a plurality of outwardly and downwardly directed gas conduits extending from the cartridge chamber to the exterior of the generator through the bottom of the body portion, the outlets of the conduits being so arranged as to merge the gaseous discharge into a solid sheet.

2. A gas protective apparatus comprising a gas generator and means in connection therewith for producing a vertically disposed sheet of gas immediately beneath the generator, said means including a body portion having therein a longitudinally disposed cartridge chamber, a gas producing cartridge fitted within the chamber, means for igniting

the cartridge and a plurality of outwardly and downwardly directed gas conduits communicating with the cartridge chamber along the length thereof and extending to the exterior of the generator through the bottom of the body portion, the outlets of the conduits being arranged so as to merge their gaseous discharges into a solid sheet. 70

3. A gas protective apparatus comprising a gas generator and means in connection therewith for producing a vertical sheet of gas immediately beneath the generator, said means including a body portion having a cartridge chamber, a gas producing cartridge disposed within the chamber, electric means in connection with the cartridge for effecting its ignition and a plurality of outwardly and downwardly directed gas conduits extending from the cartridge chamber to the exterior of the generator through the bottom of the body portion, the outlets of the conduits being so arranged as to merge the gaseous discharge into a solid sheet. 75

4. A gas protective apparatus comprising a gas generator and means in connection therewith for producing a vertical sheet of gas immediately beneath the generator, said means including a body portion having a discharge outlet in its bottom, a gas source located interior of the body portion and means for conducting the gas from said source in an outwardly and downwardly curved path to the discharge outlet, whereby the gaseous particles issuing from the outlet will tend to remain in a vertical plane. 80

5. A gas protective apparatus comprising a gas generator and means in connection therewith for producing a vertical sheet of gas immediately beneath the generator, said means including a body portion having a discharge outlet in the bottom thereof, a source of gas located interior of the body portion and an outwardly and downwardly curved conduit interconnecting the gas source with said outlet, whereby the motion imparted by the curved conduit to the gaseous particles traversing it will cause said particles, after leaving the outlet, to remain in a vertical plane. 85

6. A gas protective apparatus comprising a gas generator and means in connection therewith for producing a vertical sheet of gas immediately beneath the generator, said means including a body portion having a series of discharge outlets formed in the bottom thereof, a source of gas supply interior of said body portion and a plurality of outwardly and downwardly curved conduits interconnecting the source of gas supply with said discharge outlets, whereby the motion transmitted to the gaseous particles traversing the conduit will tend to restrict said particles, after leaving the outlets to a vertical plane. 90

7. A gas protective apparatus shaped to conform to the general configuration and con-

- stitute a portion of the supporting fixture upon which it is adapted to be mounted and comprising a gas generator and means in connection therewith for producing a vertical sheet of gas immediately beneath the generator, said means including a body portion having a plurality of aligned discharged outlets in its bottom, a gas source located interior the body portion and means for conducting the gas from said source in an outwardly and downwardly curved path to the discharged outlets whereby the gaseous particles issuing from the outlets will tend to remain in a vertical plane.
- 15 8. A gas protective apparatus shaped to conform to the general configuration of and harmonize with the supporting fixture upon which it is adapted to be mounted, said means including a body portion having a series of aligned outlets extending longitudinally thereof, a gas source located interior the body portion, means for conducting the gas from said source to said outlets and means in connection with the last-mentioned means to impede a downward movement of the particles as they issue from the outlets whereby said gaseous particles will tend to remain in a vertical plane.
